GEORGE W. JACKSON, OF BELLEVILLE, ILLINOIS, ASSIGNOR TO THE GEORGE W. JACKSON NEW MARKING COMPANY, OF BELLEVILLE, ILLINOIS.

MOLD.

1,261,543.

Specification of Letters Patent.

Patented Apr. 2, 1918.

Application filed August 27, 1917. Serial No. 188,394.

To all whom it may concern:

Be it known that I, GEORGE W. JACKSON, a citizen of the United States, residing at Belleville, in the county of St. Clair and State of Illinois, have invented certain new and useful Improvements in Molds, of which the following is a specification.

This invention relates to molds for plastic material and more particularly to a mold 10 for use in the production of cement land, road, and street markers.

It is one aim of the invention to provide a mold of the class mentioned so constructed that it may be conveniently and quickly 15 manipulated to produce the markers. Incidentally, the invention aims to so construct the several parts of the mold that they may be quickly assembled and disassembled.

Another aim of the invention is to provide 20 a mold so constructed that any desired combination of letters or other characters may be quickly arranged upon the bed of the mold so that with but little trouble and in a short time, the mold may be adapted to 25 produce markers bearing different combinations of letters, etc., constituting street, and road designations and the like.

In the accompanying drawings:

Figure 1 is a plan view of the mold arranged 30 to produce a marker such as shown in Fig. 13 of the drawings;

Fig. 2 is a side elevation of the mold arranged as shown in Fig. 1;

Fig. 3 is a vertical transverse sectional view on the line 3—3 of Fig. 1;

Fig. 4 is a perspective view of the base of the mold;

Fig. 5 is a group perspective view illustrating one side wall and one end wall of 40 the mold removed from the base;

Fig. 6 is a perspective view illustrating the other end wall of the mold;

Fig. 7 is a perspective view of one form of marker.

Fig. 8 is a vertical sectional view illustrating the manner of mounting one of the character molding elements of the device.

The base of the mold embodying the present invention includes side members which 50 are indicated by the numeral 1 and an end member 2, an end member 3, and an intermediate cross member 4, the members 2, 3 and 4 extending between and connecting the said side members 1. Beyond the end members 2 and 3 the side members 1 are pref-

erably extended to form handles 5 whereby the said base and the parts which are to be arranged thereon may be carried and whereby the mold may be readily manipulated to discharge the marker therefrom after the molding operation. Extending between the members 2 and 4 and preferably seating in recesses 6 and 7 formed in the upper sides of the said members, respectively, is a plate 8 which constitutes a portion of the bottom 60 of the mold, the side edges of the plate 8 diverging to a greater or less degree in the direction of the end member 2 whereby the anchoring post or base of the marker to be produced in the arrangement of the mold 70 shown in Figs. 1 to 6, inclusive, will be slightly increased in width in the direction of its lower end. The remainder of the bottom of the mold is located between the end member 3 and intermediate cross member 4 75 and this portion of the bottom may be formed separate from the base of the mold and seat into the upper side thereof or it may constitute an integral part of the mold. In the present illustration the side members 80 1 of the mold base are formed with recesses in their upper sides indicated by the numeral 9 and seated in these recesses and secured in any suitable manner are the sides 10 of a bottom plate which is preferably of metal, 85 and the upper surface of which may be smoothly finished so that the portion of the marker bearing the road or other designation will be produced with a smooth face. Transverse members 11, 12 and 13 extend 90 between the upper sides of the side members 10 and, in effect, these several parts may be considered as an integral plate having transversely extending slots or openings. The adjacent or opposing edges of the portions 95 11, 12 and 13 are rabbeted, as at 14, to provide seats for character molding members each of which comprises a plate 15 having a character stamped or otherwise formed in its upper face, as indicated by the numeral 100 16. The under side of each character plate 15 is formed at its lateral edges with depending flanges 17 which terminate, however, short of the ends of the plate so that the end edge portions of each plate may rest 105 flat upon shoulders or ledges provided by the formation of rabbets 14. The rabbets 14 are of a depth substantially equal to the thickness of the ends of the plates comprising the character molding elements so 110

that the upper faces of the plates, when arranged within the mold, will be flush with the upper surfaces of the portions 11, 12 and 13. It will be understood that any desired combination of characters may be arranged within the mold and that while in the drawings the mold base is illustrated as having but two transverse openings to receive the character molding elements, the said base 10 may have but a single opening or any desired number of openings so that as many lines of characters as may be desired may be molded upon the face of the marker to be produced by the mold.

15 The side walls of the mold are designed to be mounted upon the base, above described, and the shape of the side walls, of course, determines the contour of the marker to be produced. Each side wall of the mold includes a portion 18, a portion which is offset and which is indicated by the numeral 19, and a portion 20, the portion 19 extending between and connecting the adjacent ends of the said portions 18 and 20. The portions 25 19 and 20 have parallel upper and lower edges or, in other words, are of the same height throughout, but the portion 18 gradually increases in height from its end which connects with the portion 19 to its opposite or free end. Also, while the portions 19 and 20 extend at right angles with respect to each other, the portion 18 extends at an acute angle to the portion 19 so that when the two side walls of the mold are disposed 30 upon the base heretofore described, the wall portions 18 will diverge to a degree corresponding to the degree of divergence of the side edges of the plate 8 upon the upper face of which plate these portions of the side walls rest. The portions 19 of the side walls rest upon the upper edge of the intermediate cross member 4 and the portions 20 of the side walls rest upon the upper faces of the members 11, 12 and 13 at their ends. In 35 order to prevent relative displacement of the side walls when disposed upon the base of the mold, the plate 8 is provided adjacent its side edges with sockets 21 which receive studs 22 upon the lower edges of the portions 50 18 of the side walls. One end wall of the mold is indicated by the numeral 23 and is in the nature of a plate designed to be seated at its side edges in grooves 24 formed in the opposing faces of the portions 18 of the side walls at their higher ends. Secured 55 upon the upper edge of the plate 23 comprising one end wall of the mold, is a length of strap iron 25, the ends of which project beyond the side edges of the said plate 23 60 and extend over the upper edges of the portions 18 of the side walls and are provided with down-turned terminals 26 which extend downwardly beside the outer faces of the said portions 18. In this manner the 65 portions 18 are further held against relative

displacement or separation. The other end wall of the mold comprises a body 27 which is formed with a recess 28 in one side between its ends. The body 27 is provided upon its under side with studs 29 which are 70 designed to seat in sockets 30 formed in the upper edge of the end member 3 of the base of the mold. Secured upon the outer face of the wall member 27 at each end thereof is a staple or similar element 31 while hingedly 75 connected, as at 32, to the free end of the portion 20 of each side wall of the mold is a tongue 33 having a slot 34 to receive the staple 31. It will now be understood, and particularly by reference to Fig. 1 of the 80 drawings, that after the side walls of the mold have been disposed upon the base, as also the end wall 27, the tongue 33 may be swung into engagement with the staples 31 so as to prevent relative displacement of the 85 portions 20 of the two side walls, both with relation to each end and with relation to the end wall 27. In molding a marker of the form shown in Fig. 7 of the drawings, it is desirable that the back or rear face of the 90 marker shall be reinforced by continuing the post or supporting portion of the marker to the top of the said head. In order that this may be accomplished there are provided two members designed to constitute ex- 95 tensions of the upper portion of the member 18 of each side wall. Each of these extension members is indicated by the numeral 35 and is decreased in thickness from one end to the other end and is provided upon 100 its under side at its thicker end with a stud 36 designed to seat in a socket 37 formed in the respective wall portion 18, the upper edge of the wall portion at the smaller end thereof being recessed, as at 38, to receive 105 the said thicker end of the respective extension member 35. The said member 35 is also formed upon its under side at its other end with a stud 39 designed to seat in a socket 40 formed in the upper side of the end wall 27, 110 the sockets 40 being located at the opposite sides of the recess 28.

In preparing the mold the character molding members are suitably arranged upon the base and the mold parts are assembled with the exception of the members 35. The cement mixture is then poured into the mold and stamped and otherwise caused to settle and if desired a thin layer of cement may be dusted on to that portion of 115 the bottom of the mold which is to produce the character bearing face of the marker so that this face, in the finished article, will be smooth and present a finished appearance. After the cement has been caused to properly settle the members 35 are placed in position and more cement is poured into the space between these members and between the upper edge portions of the wall members 120 18 and the end wall 23.

Having thus described the invention, what is claimed as new is:

1. In a mold of the class described, a base, a mold bottom member arranged on part of the base, a wider mold bottom member forming a continuation of the first-mentioned member, side walls removably disposed upon the base and conforming to the outlines of the sides of the said bottom members, the portions of the side walls which extend above the first-mentioned bottom member being of greater height than the other portions of the side walls, and members constituting extensions of the first-mentioned portions of the said side walls. 10
2. In a mold of the class described, a base, a mold bottom member arranged on part of the base, a wider mold bottom member forming a continuation of the first-mentioned member, side walls removably disposed upon the base and conforming to the outlines of the sides of the said bottom members, the portions of the side walls which extend above the first-mentioned bottom member being of greater height than the other portions of the side walls, members 15
3. In a mold of the class described, a mold wall having a seat provided at its opposite sides with supporting ledges, and below the ledges with shoulders and character molding elements arranged to be selectively disposed upon said seat and each member comprising a character bearing body, and side flanges projecting from the under face of the said body and terminating short of the ends of the body whereby the edges of the body beyond the ends of the flanges may be disposed to rest upon said ledges with the flanges extending between the said shoulders. 20
4. In a mold of the class described, a mold wall having a seat provided at its opposite sides with supporting ledges, and below the ledges with shoulders and character molding elements arranged to be selectively disposed upon said seat and each member comprising a character bearing body, and side flanges projecting from the under face of the said body and terminating short of the ends of the body whereby the edges of the body beyond the ends of the flanges may be disposed to rest upon said ledges with the flanges extending between the said shoulders. 25

constituting extensions of the first-mentioned portions of the said side walls, the said extension members extending over the second-mentioned bottom portion and the upper edges thereof, and the upper edges of the first-mentioned portions of the side walls being continuously inclined downwardly in the direction of the outer ends of the extensions. 30

35

3. In a mold of the class described, a mold wall having a seat provided at its opposite sides with supporting ledges, and below the ledges with shoulders and character molding elements arranged to be selectively disposed upon said seat and each member comprising a character bearing body, and side flanges projecting from the under face of the said body and terminating short of the ends of the body whereby the edges of the body beyond the ends of the flanges may be disposed to rest upon said ledges with the flanges extending between the said shoulders. 40

4. In a mold of the class described, a mold wall having a seat provided at its opposite sides with supporting ledges, and below the ledges with shoulders and character molding elements arranged to be selectively disposed upon said seat and each member comprising a character bearing body, and side flanges projecting from the under face of the said body and terminating short of the ends of the body whereby the edges of the body beyond the ends of the flanges may be disposed to rest upon said ledges with the flanges extending between the said shoulders. 45

50

In testimony whereof I affix my signature.

GEORGE W. JACKSON. [L. s.]
